UNITED STATES PATENT OFFICE

JOHN M. SCHILLING, OF LIMA, OHIO

BOTTLE COOLER

Application filed September 22, 1928. Serial No. 307,645.

My invention relates to an improved construction of cooler for bottled goods, for example soft drinks, so that the bottles may be conveniently passed through a cooling medium and be chilled to impart a pleasing coolness to their contents.

I am aware that bottle coolers of the type referred to have been proposed heretofore, consisting of rotary bottle carriers having radial compartments for the bottles, combined with riding tracks for retaining the bottles in the compartments of the carriers, during movement of the bottles by rotation of the carriers through the cooling medium, for example ice water, contained in the tank in which the carriers and tracks are located. My present invention pertains to improvements in bottle coolers of the type just described, by which bottles of varying sizes may be handled by the bottle carriers without danger of having them slip from the riding tracks, and by which the bottles in the carriers are otherwise prevented from improperly leaving the compartments of the carriers. I have found in operating bottle coolers of the type under consideration, that where the bottle carrier is rotated rapidly, the centrifugal force exerted on the bottles when they are in the upper half of the carrier, tends to throw them from the compartments of the carrier and in some cases sufficiently to cause them to jam against the casing of the cooler with sufficient force to break the bottles. By my present invention, I prevent this result by providing a shield around and above the bottle carriers to prevent their leaving the compartments in the carriers excepting when the bottles are in alignment with the service openings of the casing of the cooler. By my invention I further safeguard against bottle breakage, by leaving a considerable space between the riding tracks and the inner surface of the bottom wall of the cooler casing, for I find that bottle caps and foreign matter of different kinds find

their way into the cabinet around the bottle carriers and with damaging results, where no special provision is made for a space permitting the accumulation of foreign matter such as bottle caps, below the bottle carriers. 50

My invention will best be understood by reference to the accompanying drawings showing a preferred embodiment thereof, in which

Fig. 1 is a longitudinal, vertical, central 55 section view through my improved bottle cooler,

Fig. 2 is a transverse sectional view of the bottle cooler shown in Fig. 1, taken along the line 2—2, 60

Fig. 3 shows in a view similar to Fig. 2 a modified construction of shield surrounding the upper portions of the bottle carriers to prevent their leaving the compartments in the carriers, and 65

Fig. 4 shows in a view similar to Fig. 1, a modified form of riding track.

Similar numerals refer to similar parts throughout the several views.

As shown in Figs. 1 and 2 my bottle cooler 70 consists of a casing 10 preferably having metal walls spaced from each other and filled with heat insulating material, for example, cork, asbestos, mineral wool, or the like. The casing is open at its top and provided with a 75 cover 11, which may be removed from the casing to install the bottle carriers and to afford access to the bottle carriers and the interior of the casing whenever desired. The cover 11 is provided with service doors 12, 12 and a 80 door 13, the latter being provided to facilitate icing the cooler. Each of the doors 12 is above the central upper portions of a series of bottle carriers 14 mounted for rotary movement on a shaft 15 supported by a metal 85 framework as indicated. Each carrier supporting framework comprises two vertical metal bars 16 and 17 and a horizontally disposed rectangular frame 18 made by bending a similar metal bar so that it may be fas- 90

tened at the mid portion of its opposite sides to the vertical bars 16 and 17 to surround one series of the bottle carriers 14. The junctions of the bars 16 and 17 with the rectangular frame 18 support the ends of the shaft 15.

5 Each of the carriers 14 is provided with radial bottle compartments 19, of the general shape of the neck portions of bottles 20 of the largest size contemplated to be handled by 10 the cooler. Each of the compartments 19 is of sufficient extent radially to contain the entire neck portion of the bottle and a part of the cylindrical portion of the bottle, to the end that the bottles may be retained in radial 15 position in the compartments. The projecting bottom portions of the bottles provide for the direct action of the cooling medium upon the bottles, and permit readily grasping the bottles to place them in the carriers and 20 remove them from the same.

Each of the series of bottle carriers is provided with a plurality of metal riding tracks 21, each of which is mounted concentrically with the shaft 15 around one of the 25 bottle carriers 14, substantially in its mid plane, the distance from each riding track 21 to the outer surface of the corresponding carrier 14, being such preferably as to permit but slight clearance between the riding track 30 and the bottom of the bottle of largest size to be handled by the cooler. The riding tracks 21 are preferably supported in the position and relation described, by a metal bar 22 extending transversely between the bars 35 16 and 17, a substantial distance, for example from two to four inches, above the inner surface of the bottom of the casing 10. The lower ends of the bars 16 and 17 constitute legs holding the riding tracks in the elevated 40 position referred to. In addition, the riding tracks 21 are supported in the position described, by engagement with the metal frame 18. Additional supports may be given the riding tracks 21 by supplementary rectangular frames 23 and 24 bent from metal bars to 45 the form indicated and supported at mid portions of their opposite sides by the frame 18 so that the tracks 21 rest against the horizontally disposed members of these frames 23 50 and 24. The riding tracks 21 preferably extend around the upper portions of the carriers 14 excepting immediately below the service doors 12, where the tracks are discontinued to permit the insertion of bottles into 55 and the removal of the same from the bottle carriers.

The riding tracks 21, around the lower halves of the carriers 14, constitute supports for the bottles carried by the carriers, since 60 when they are below the shaft 15, the bottles tend to slip from the compartments 19, and are prevented from so doing by the riding tracks 21. Above the shaft 15, the tendency of the bottles, due to their weight is to assume 65 a position in the compartments 19 as near to

the shaft 15 as the shape and size of the bottles will permit, and there is normally therefore, no riding of the bottles on the extensions of the riding tracks 21 above the frame 18. When one of the carriers 14 is rotated vigorously however, the centrifugal effect exerted on the bottles in the carrier tends to throw them outwardly from their compartments, even when they are above the shaft 15 and the extensions of the riding tracks 21 70 above the frame 18, therefore constitute shields or guards to prevent the bottles leaving the compartments.

In Fig. 3, I illustrate a somewhat different form of shield or guard where the riding tracks 21^a do not extend substantially above the horizontal metal frame 18. In this case the shield or guard consists of a piece of sheet metal 25 bent to substantially the curvature of the riding tracks 21 and held in 80 place by bent metal bars 28 supported at their ends from the frame 18, which sheet metal piece 25 may extend over and shield all of the bottle carriers 14 of a series of carriers. 85

The clearance space between the bar 22 and 90 the bottom of the casing 10 provides a substantial refuse receptacle for bottle caps, broken glass and any foreign matter that may find its way into the cooler and that would otherwise interfere with turning the 95 carriers to move the bottles through the cooler.

In addition to the riding tracks 21, I find it desirable to provide each carrier framework with guide tracks 27 which are circular in conformation and of a radius to engage the opposite side walls of the bottles if they for any reason depart axially from substantially radial position in the compartments 19, the distance between any two of the guide tracks 27 provided for one of the bottle carriers, being slightly greater than the body diameter of the largest bottle to be handled by the cooler. The guide tracks 27 may be continuous rings as indicated, since they do not interfere with the insertion of the bottles into or the removal of the same from the bottle carriers, or they may be of any other desired extent, and they are supported centrally around the shaft 15 by metal brackets 29 secured to the bar 22 and to the horizontal members of the bent frames 23 and 24, and by the frame 18. It frequently happens in handling soft drinks by means of a cooler of the kind described, that bottles of somewhat different size and shape must be handled for 100 different drinks, although the bottles have substantially the same capacity. I have found that where the bottles have relatively long slender necks, as compared with the largest size bottle for which the cooler is 105 designed, the bottles readily tilt in the compartments and so much so at times as to leave the riding tracks entirely and jam against the supporting frame and casing, unless special provision is made to prevent it. The guide 110

tracks 27 prevent bottles of any size that the cooler is designed to handle, from leaving the riding tracks 21, and thus bottle breakage and damage to the cooler is prevented. 5 Metal plates 28, which may be perforated if desired, are supported by the carrier frames in spaced relation between the frames, to leave an icing compartment 30 between them, so that ice may be retained in the icing compartment and cool the water contained in the lower part of the casing, without the possibility of the ice finding its way between the bottles, which would tend to interfere with their movement through the cooling medium 10 and break the bottles by jamming between them.

While the riding tracks shown in Fig. 1 are shown as of circular cross-section, I do not limit myself to that particular form, but 20 I may employ, if desired, other forms, for example, a rectangular cross-section, as shown at 21^b in Fig. 4. Any desired shape and size of bar may be employed for the riding tracks and for the guide tracks, it being desirable, 25 however, that the shape and size used, will produce small friction between the bottles and the tracks, that the tracks will be sufficiently strong and stiff to carry the loads placed upon them, and that they provide 30 ample clearance around them to permit bottle caps, broken glass, and foreign matter generally, to find their way into the refuse receptacle.

The riding and guide tracks may be secured 25 to their supporting bars and brackets in any convenient manner, for example, by soldering, brazing or spot-welding them to said supports.

While I have shown my invention in the 40 particular embodiment above described, it will be understood that I do not limit myself to this exact construction as I may employ equivalents known to the art at the time of the filing of this application without departing 45 from the scope of the appended claims.

What I claim is:

1. In a bottle cooler, the combination of a casing, rotary bottle carriers, a framework supporting said carriers in substantially vertical planes for rotary movement in said casing, riding tracks around said carriers for holding bottles therein, and guide tracks in planes substantially parallel with the planes of said riding tracks for engaging bottles in 55 said carriers to hold said bottles on said riding tracks, said framework including laterally extending bars supporting said tracks and legs extending below said tracks and below the lowermost one of said supporting bars to rest upon the bottom of said casing and holding said tracks a substantial distance above the bottom of said casing constituting the lower part of said casing a refuse receptacle below said tracks, said tracks having substantial clearance spaces around them permitting 60

foreign matter to pass freely into said refuse receptacle.

2. In a bottle cooler, the combination of a casing, rotary bottle carriers, a framework supporting said carriers in substantially vertical planes for rotary movement in said casing, and riding tracks around said carriers for holding bottles therein, said framework including laterally extending bars supporting said tracks and legs extending below said tracks and below the lowermost one of said supporting bars to rest upon the bottom of said casing and holding said tracks a substantial distance above the bottom of said casing constituting the lower part of said casing a refuse receptacle below said tracks, said tracks having substantial clearance spaces around them permitting foreign matter to pass freely into said refuse receptacle. 70

3. In a bottle cooler, the combination of a casing, rotary bottle carriers, a framework supporting said carriers in substantially vertical planes for rotary movement in said casing, riding tracks around said carriers for holding bottles therein, and guide tracks in planes substantially parallel with the planes of said riding tracks for engaging bottles in said carriers to hold said bottles on said riding tracks, said framework including laterally extending bars supporting said tracks and legs extending below said tracks and below the lowermost one of said supporting bars to rest upon the bottom of said casing and holding said tracks a substantial distance above the bottom of said casing constituting the lower part of said casing a refuse receptacle below said tracks, said tracks having substantial clearance spaces around them permitting foreign matter to pass freely into said refuse receptacle. 80

4. In a bottle cooler, the combination of a casing, rotary bottle carriers, a framework supporting said carriers in substantially vertical planes for rotary movement in said casing, riding tracks around said carriers for holding bottles therein, and guide tracks in planes substantially parallel with the planes of said riding tracks for engaging bottles in 90

5. In a bottle cooler, the combination of a casing, rotary bottle carriers, a framework supporting said carriers in substantially vertical planes for rotary movement in said casing, riding tracks around said carriers for holding bottles therein, and guide tracks in planes substantially parallel with the planes of said riding tracks for engaging bottles in said carriers to hold said bottles on said riding tracks, said framework including laterally extending bars supporting said tracks and legs extending below said tracks and below the lowermost one of said supporting bars to rest upon the bottom of said casing and holding said tracks a substantial distance above the bottom of said casing constituting the lower part of said casing a refuse receptacle below said tracks, said tracks having substantial clearance spaces around them permitting foreign matter to pass freely into said refuse receptacle, said riding tracks extending above the axes of said carriers and comprising shields preventing egress of bottles from said carriers by centrifugal action, and said guide tracks comprising continuous rings.

6. In a bottle cooler, the combination of a casing, rotary bottle carriers, a framework supporting said carriers in substantially vertical planes for rotary movement in said casing, riding tracks around said carriers for holding bottles therein, guide tracks in planes substantially parallel with the planes of said riding tracks for engaging bottles in said carriers to hold said bottles on said riding tracks, said framework including laterally extending bars supporting said tracks and legs extending below said tracks and below the lowermost one of said supporting bars to rest upon the bottom of said casing and holding said tracks a substantial distance above the bottom of said casing constituting the lower part of said casing a refuse receptacle below said tracks, said tracks having substantial clearance spaces around them permitting foreign matter to pass freely into said refuse receptacle, and shields around the upper portions of said carriers preventing egress of bottles from said carriers by centrifugal action.

7. In a bottle cooler, the combination of a casing, rotary bottle carriers, a framework supporting said carriers in substantially vertical planes for rotary movement in said casing, riding tracks around said carriers for holding bottles therein, guide tracks in planes substantially parallel with the planes of said riding tracks for engaging bottles in said carriers to hold said bottles on said riding tracks, said framework including laterally extending bars supporting said tracks and legs extending below said tracks and below the lowermost one of said supporting bars to rest upon the bottom of said casing and holding said tracks a substantial dis-

tance above the bottom of said casing constituting the lower part of said casing a refuse receptacle below said tracks, said tracks having substantial clearance spaces around them permitting foreign matter to pass freely into said refuse receptacle, and shields around the upper portions of said carriers preventing egress of bottles from said carriers by centrifugal action, said guide tracks comprising continuous rings.

8. In a bottle cooler, the combination of a casing, rotary bottle carriers, a framework supporting said carriers in substantially vertical planes for rotary movement in said casing, and riding tracks around said carriers for holding bottles therein, said framework including laterally extending bars supporting said tracks and legs extending below said tracks and below the lowermost one of said supporting bars to rest upon the bottom of said casing and holding said tracks a substantial distance above the bottom of said casing constituting the lower part of said casing a refuse receptacle below said tracks, said tracks having substantial clearance spaces around them permitting foreign matter to pass freely into said refuse receptacle, said riding tracks extending above the axes of said carriers and comprising shields preventing egress of bottles from said carriers by centrifugal action.

9. In a bottle cooler, the combination of a casing, rotary bottle carriers, a framework supporting said carriers in substantially vertical planes for rotary movement in said casing, riding tracks around said carriers for holding bottles therein, said framework including laterally extending bars supporting said tracks and legs extending below said tracks and below the lowermost one of said supporting bars to rest upon the bottom of said casing and holding said tracks a substantial distance above the bottom of said casing constituting the lower part of said casing a refuse receptacle below said tracks, said tracks having substantial clearance spaces around them permitting foreign matter to pass freely into said refuse receptacle, and shields around the upper portions of said carriers preventing egress of bottles from said carriers by centrifugal action.

10. In a bottle cooler, the combination of a casing, rotary bottle carriers, a framework supporting said carriers in substantially vertical planes for rotary movement in said casing, riding tracks around said carriers for holding bottles therein, guide tracks in planes substantially parallel with the planes of said riding tracks for engaging bottles in said carriers to hold said bottles on said riding tracks, and supports holding said tracks a substantial distance above the bottom of said casing constituting the lower part of said casing a refuse receptacle below said tracks, said tracks having substantial clearance

spaces around them permitting foreign matter to pass freely into said refuse receptacle.

11. In a bottle cooler, the combination of a casing, rotary bottle carriers, a framework supporting said carriers in substantially vertical planes for rotary movement in said casing, riding tracks around said carriers for holding bottles therein, and supports holding said tracks a substantial distance above the bottom of said casing constituting the lower part of said casing a refuse receptacle below said tracks, said tracks having substantial clearance spaces around them permitting foreign matter to pass freely into said refuse receptacle.

12. In a bottle cooler, the combination of a casing, rotary bottle carriers, a framework supporting said carriers in substantially vertical planes for rotary movement in said casing, riding tracks around said carriers for holding bottles therein, and guide tracks in planes substantially parallel with the planes of said riding tracks for engaging bottles in said carriers to hold said bottles on said riding tracks, said guide tracks comprising continuous rings.

13. In a bottle cooler, the combination of a casing, rotary bottle carriers, a framework supporting said carriers in substantially vertical planes for rotary movement in said casing, riding tracks around said carriers for holding bottles therein, and guide tracks in planes substantially parallel with the planes of said riding tracks for engaging bottles in said carriers to hold said bottles on said riding tracks, said riding tracks extending above the axes of said carriers and comprising shields preventing egress of bottles from said carriers by centrifugal action.

14. In a bottle cooler, the combination of a casing, rotary bottle carriers, a framework supporting said carriers in substantially vertical planes for rotary movement in said casing, riding tracks around said carriers for holding bottles therein, guide tracks in planes substantially parallel with the planes of said riding tracks for engaging bottles in said carriers to hold said bottles on said riding tracks, and shields around the upper portions of said carriers preventing egress of bottles from said carriers by centrifugal action.

15. In a bottle cooler, the combination of a casing, rotary bottle carriers, a framework supporting said carriers in substantially vertical planes for rotary movement in said casing, riding tracks around said carriers for holding bottles therein, guide tracks in planes substantially parallel with the planes of said riding tracks for engaging bottles in said carriers to hold said bottles on said riding tracks, and supports holding said tracks a substantial distance above the bottom of said casing constituting the lower part of said casing a refuse receptacle below said tracks, said tracks having substantial

clearance spaces around them permitting foreign matter to pass freely into said refuse receptacle, said guide tracks comprising continuous rings.

16. In a bottle cooler, the combination of a casing, rotary bottle carriers, a framework supporting said carriers in substantially vertical planes for rotary movement in said casing, riding tracks around said carriers for holding bottles therein, guide tracks in planes substantially parallel with the planes of said riding tracks for engaging bottles in said carriers to hold said bottles on said riding tracks, and supports holding said tracks a substantial distance above the bottom of said casing constituting the lower part of said casing a refuse receptacle below said tracks, said tracks having substantial clearance spaces around them permitting foreign matter to pass freely into said refuse receptacle, said riding tracks extending above the axes of said carriers and comprising shields preventing egress of bottles from said carriers by centrifugal action.

17. In a bottle cooler, the combination of a casing, rotary bottle carriers, a framework supporting said carriers in substantially vertical planes for rotary movement in said casing, riding tracks around said carriers for holding bottles therein, guide tracks in planes substantially parallel with the planes of said riding tracks for engaging bottles in said carriers to hold said bottles on said riding tracks, supports holding said tracks a substantial distance above the bottom of said casing constituting the lower part of said casing a refuse receptacle below said tracks, said tracks having substantial clearance spaces around them permitting foreign matter to pass freely into said refuse receptacle, said riding tracks extending above the axes of said carriers and comprising shields preventing egress of bottles from said carriers by centrifugal action.

18. In a bottle cooler, the combination of a casing, rotary bottle carriers, a framework supporting said carriers in substantially vertical planes for rotary movement in said casing, riding tracks around said carriers for holding bottles therein, and supports holding said tracks a substantial distance above the bottom of said casing constituting the lower part of said casing a refuse receptacle below said tracks, said tracks having substantial clearance spaces around them permitting foreign matter to pass freely into said refuse receptacle, said riding tracks extending above the axis of said carriers and comprising shields preventing egress of bottles from said carriers by centrifugal action.

19. In a bottle cooler, the combination of a casing, rotary bottle carriers, a framework supporting said carriers in substantially vertical planes for rotary movement in said casing, riding tracks around said carriers for

holding bottles therein, supports holding said tracks a substantial distance above the bottom of said casing constituting the lower part of said casing a refuse receptacle below said tracks, said tracks having substantial clearance spaces around them permitting foreign matter to pass freely into said refuse receptacle, and shields around the upper portions of said carriers preventing egress of bottles from said carriers by centrifugal action.

In witness whereof, I hereunto subscribe my name this 15 day of Sept., A. D. 1928.

JOHN M. SCHILLING.
